WILLIAM C. JORDAN, OF MADISON, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 15, 1923. Serial No. 680,807.

This invention relates to telephone exchange systems and more particularly to systems involving the use of machine switching apparatus for the establishment of connections.

In exchange systems of the above mentioned character, it is desirable to enable connections to be established from distant toll points to any subscriber's line in a machine switching exchange area over the automatic switching mechanism of the exchange. In the establishment of such toll connections, it is desirable to apprise the toll operator of any conditions in the machine switching exchange which would prevent the immediate establishment of the desired connection in order that she may re-establish the partially completed connection by means of other apparatus in the machine switching exchange, or delay the establishment of the connection until such time as she thinks apparatus or trunk lines will be available for her use. Some of the conditions at the machine switching exchange through which a call may be attempted which would prevent the establishment of the connection might be due to a stuck sender or to the advance of an automatic switch to an overflow or telltale position.

It is further desirable to signal the toll operator when ringing in the machine switching office is initiated.

It is therefore the object of the present invention to enable toll calls originating at distant toll points to be completed to the lines of subscribers in a machine switching area by means of selector switches.

More particularly, it is an object of the invention to provide means at a district selector under the control of a distant toll operator for initiating the automatic application of ringing current to a wanted line and to provide means at such selector for apprising the operator of conditions at the machine switching exchange requiring her supervision.

A feature of the invention is the provision in the district selector circuit of a relay for applying ringing current to the trunks outgoing from such selector automatically initiating ringing at the office in which the call is to be terminated, said relay also being

under the control of the toll operator for re-ringing the called subscriber.

A further feature of the invention relates to the provision of means in a district selector for transmitting signals to a distant toll position when a sender has been associated with the district selector and is in condition to receive dialing impulses, when a seized sender becomes stuck and fails to function, if the district selector goes to overflow or telltale, when the establishment of a desired connection has proceeded to a point where the initiation of ringing may proceed, and when the called subscriber answers or hangs up his receiver.

This and other features contemplated in the present invention will become more clearly understood from a consideration of the accompanying drawings and the appended claims.

Referring to the drawings, Fig. 1 shows a toll line composited for simultaneous telephony and telegraphy with the necessary composite ringing equipment, a toll operator's cord and associated dialing equipment and a portion of the equipment at an outward delay operator's position.

Fig. 2 shows a line switch in which the toll line of Fig. 1 terminates.

Fig. 3 shows one of a group of district selector switches accessible from the line switch of Fig. 2 and having access to trunks outgoing to different offices of the machine switching exchange in which it is located, and a sender selector for associating the district selector with an idle central office sender.

Fig. 4 shows so much of a central office sender as is necessary to an understanding of the invention. In this figure, the sender monitor switch is shown in detail in the lower left portion of the figure, and in the right portion of the figure, the register steering switch and the "A" and "B" code registers are illustrated. The numerical registers have been omitted in order to simplify the drawing.

Fig. 5 shows a trunk circuit incoming from the terminal banks of toll district selectors, such as shown in Fig. 3, and outgoing to a full mechanical office of an exchange area. This trunk circuit is also shown as accessible from a toll key indicator opera-

tor's cord circuit shown in the upper left portion of the figure. In the lower right corner of the figure, a key indicator link associated with the operator's position is also diagrammatically illustrated.

Fig. 6 shows an incoming selector circuit in which the trunk circuit of Fig. 5 terminates, together with the control circuits thereof.

Fig. 7 shows a final selector switch accessible from the incoming selector switch of Fig. 6, together with the control circuits thereof and a multi-station line terminating in the terminal bank of said switch.

Fig. 8 is a diagram showing the manner in which the several figures of the drawing should be arranged to show the complete circuits illustrating the invention.

The toll line and associated equipment shown in part in Fig. 1 is of the type disclosed in the Patent No. 1,617,413, issued to Lewis A. Mortimer, on February 15, 1927. Only such portions thereof as are necessary to an understanding of this invention have been disclosed herein.

The toll line-switch of Fig. 2 is of the rotary type, having a clutch magnet and a stop magnet, the circuits thereof being slightly modified for the purposes of this invention.

The district selector of Fig. 3, the incoming selector of Fig. 6 and the final selector of Fig. 7 are of the well known power driven panel bank type disclosed in the patent to E. B. Craft and J. N. Reynolds 1,123,693, issued January 5, 1915, the circuits of these selectors being substantially similar to the circuits of corresponding selectors disclosed in the Patent 1,395,977 issued to F. A. Stearn and F. J. Scudder, November 1, 1921. The district selector circuit of Fig. 3 is, however, modified by the introduction of the novel features of the invention to enable this selector to function in the extension of toll connections.

The sender diagrammatically illustrated in Fig. 4 is of the general type disclosed in the patent to O. A. Kopp, No. 1,509,434 issued Sept. 23, 1924. Only such portions of the sender have been disclosed as are considered essential to an understanding of the invention.

Establishment of connection.

It is thought that the invention will be best understood from a detail description of the manner in which a toll connection may be established from the toll operator's position 125 of Fig. 1 to the subscriber's line terminating in the final selector switch 750 of a machine switching office. The toll operator at position 125, having received the instructions, in the well-known manner, for extending the desired toll connection tests for idle toll lines and assuming the line 150 to be the first idle line encountered, inserts

plug 120 into jack 121, whereupon relays 104 and 101 operate in a circuit extending from battery through the winding of marginal relay 103, winding of relay 104, normal contacts of dialing key 105, normal contacts of 70 ringing key 102, sleeve contacts of plug 120 and jack 121 to ground through the windings of relays 101 and 100. Relays 103 and 100 do not operate at this time, the former being marginal and the latter being responsive to low frequency signaling current and strong direct current only. Relay 104 in operating prepares a circuit for the supervisory lamp 106, and relay 101 at its outer armature disconnects relay 127 from the tip 75 and ring conductors of the outgoing end of the toll line and at its inner armature closes a circuit for operating relay 124. The circuit for relay 124 may be traced from the negative terminal of the high voltage battery 80 137, outer right and inner right back contacts of relay 126, winding of relay 124, left back contact of relay 126, conductor 128 over the composite leg of toll line 150, conductor 129, inner contact of relay 101, winding of polarized relay 130, back contact of relay 100 to ground. The direction of current in this circuit is such as to prevent polarized relay 130 from operating at this time. Relay 124, however, operates, closing 85 a circuit for slow-to-operate relay 122. The circuit of this relay extends from battery through the winding of the relay, the left back contact of relay 119, the back contact of relay 123 to ground at the contact of relay 100 124. Relay 122 upon operating closes a circuit extending from ground through its contact over conductor 140 to battery through the winding of relay 208, which latter relay operates and in turn establishes an obvious circuit for relay 211. 105

Relay 211 at its inner left contact establishes a circuit for relay 119 extending from battery through the winding of relay 119, conductor 139 to ground at the inner left contact of relay 211. Relay 119, in attracting its right armature, disconnects the ringing relay 118 from conductor 128 and the tip side of the toll line during the dialing period and at its left armature opens the original energizing circuit for relay 122, which relay thereupon releases removing ground from the winding of relay 208. Relay 208, however, remains operated in a circuit extending from battery through its winding, conductor 140, the left front contact of relay 119, the back contact of relay 123 to ground at the contact of relay 124. At its outer right contact, relay 211 prepares a circuit for relay 214 and at its inner right contact 115 prepares a circuit for relays 222 and 216. At its outer left contact, relay 211 establishes a circuit for the stop magnet 212 which may be traced from battery through the winding of magnet 212, the outer right 120 125 130

contact of relay 214, the back contact of relay 216, thence to ground at the outer left contact of relay 211. Magnet 212 upon energizing closes an obvious circuit for the rotary magnet 218 of the line switch 250 which thereupon operates, causing the line switch to start hunting for an idle district selector. The hunting movement of the line switch continues until the brush 221 engages a test terminal associated with an idle district selector, the test terminals of idle district selectors being marked by full battery potential. It will be assumed that the district selector 350 of Fig. 3 is the first idle selector found idle. When brush 221 encounters terminal 220, a circuit is established from battery, through resistance 305, contacts of cam 304, outer right back contact of relay 303, left back contact of relay 302, lower contacts of cam 301, test terminal 220, brush 221, inner right contact of relay 211, high and low resistance windings of relay 222 to ground, through the winding of relay 216. Due to the inclusion of the high resistance left winding of relay 222, relay 216 does not receive sufficient current to operate in this circuit but relay 222 energizes, short circuiting its high resistance winding, thereby changing the potential upon multiples of terminal 220 to mark the selected district as busy to other line switches having access thereto and reducing the resistance of the test circuit to such an extent as to permit the operation of relay 216. Relay 216, upon operating, opens the circuit of magnet 212 which, in turn, opens the circuit of rotary magnet 218 and stops the rotation of the brushes of the switch 250. At its front contact, relay 216 also establishes a circuit for the cut-off relay 214 which may be traced from battery, through the winding of relay 214, the front contact of relay 216, thence to ground at the outer left contact of relay 211. Relay 214, in attracting its outer right contact, opens the circuit of magnet 212 at a second point. Relay 214 also locks itself under the control of relay 211 in a circuit extending from battery through its winding, the outer right contact of relay 211 to ground over the inner right contact of relay 214. At its two outer left contacts relay 214 connects conductors 200 and 201 extending to the tip and ring brushes 298 and 245 respectively of switch 250 to contacts of relay 228 for the purpose to be explained hereinafter. Relay 214 at its inner left contact establishes a circuit for energizing the sleeve relay 303 of the selected district selector, which may be traced from battery, through the winding of sleeve relay 303, terminal 275, brush 241 to ground at the inner left contact of relay 214. Relay 303 upon operating disconnects battery 305 from the test terminal 220 by opening its outer right back contact, thus marking the district selector

busy to all line switches having access thereto. The removal of battery potential from the terminal 220 also causes the release of relays 216 and 222.

At its inner right front contact, relay 303 establishes a circuit for relay 307 which may be traced from battery through the left winding of relay 307, the left contacts of cam 306 to ground at the inner right front contact of relay 303. Relay 307 upon energizing closes a circuit for advancing sequence switch 310 out of its normal position 1 into position 2. This circuit extends from battery, through the magnet winding of sequence switch 310, the upper left contact of cam 324, the outer left front contact of relay 307 to ground at the right contact of cam 308. As soon as the sequence switch leaves position 1, the original energizing circuit of relay 307 is opened at the upper left contact of cam 306 but relay 307 is maintained energized at this time over a locking circuit extending through its right winding, right front contact, the lower right and upper left contacts of cam 309 to ground. With sequence switch 310 in position 2 and relay 307 energized, a circuit is established for starting the hunting movement of the sender selector switch 325 in search of an idle central office sender. The switch starts through the operation of stop magnet 311 over a circuit extending from battery through its winding, the back contact of relay 315, the left contacts of cam 308, thence to ground through the inner right front contact of relay 303. Magnet 311, upon energizing, closes an obvious circuit for the rotary magnet 312 of the switch 325, the switch 325 being advanced only if its test brush 313 engages a test terminal upon which full battery potential is encountered. All idle senders are marked by full battery potential on the multiple test terminals thereof appearing in the banks of all sender selector switches. It will be assumed that the sender shown in Fig. 4 is the first idle sender encountered. When, therefore, brush 313 engages terminal 317 a circuit is established from battery through the back contact of relay 400, terminal 317, brush 313, both windings of relay 314, winding of relay 315 to ground, through the lower contact of cam 316. Relay 314 energizes in this circuit but relay 315 does not energize due to the inclusion of the high resistance right winding of relay 314 in series therewith. As soon, however, as relay 314 energizes, it short-circuits its own right winding, thereby changing the potential on the multiples of test terminal 317 for marking the selected sender as busy to all sender selectors having access thereto, and permitting sufficient current to flow through the winding of relay 315 to cause its energization. With relay 315 energized, the circuit of stop magnet 311 is opened, whereupon

the circuit of rotary magnet 312 is opened and the brushes of the sender selector thereby brought to rest. At its front contact, relay 315 also establishes a circuit for relay 318 which may be traced from battery through resistance 305, winding of relay 318, front contact of relay 315, left contacts of cam 308 to ground at the inner right contact of relay 303. Relay 318 upon energizing 5 locks over its innermost right contact and the inner left contact of relay 319 to ground at the inner right front contact of relay 303. At its intermediate right armature contacts, relay 318 prepares the fundamental circuit 10 over brushes 326 and 327. At its left front contact, relay 318 establishes a circuit for advancing sequence switch 310 out of position 2 and into position 3. This circuit may be traced from battery, through the winding 15 of sequence switch 310, the lower right and upper left contacts of cam 320 to ground at the left front contact of relay 318. As soon as sequence switch 310 leaves position 2, the holding circuit of relay 307 is opened at 20 the lower right contact of cam 309, and relay 307 thereupon deenergizes. 25

With sequence switch 310 in position 3 and relay 318 energized, a circuit is established for relay 402 of the selected sender 30 and relays 302 and 323 of the district selector. This circuit may be traced from battery, through the winding of relay 323, the upper right and lower left contacts of cam 321 and in parallel therewith through 35 the winding of relay 302 and the lower contacts of cam 321, thence over the outer right contact of relay 318, brush 328, left back contact of relay 401, intermediate and left windings of relay 402 to ground. Relay 323 40 being marginal does not operate in this circuit but relays 302 and 402 operate, relay 302 being functionless at this time. Upon the operation of relay 402, an obvious circuit is established for relay 400 which at its contact removes battery potential from the 45 multiples of test terminal 317, thereby marking the selected sender as busy to all the sender selectors having access thereto. Relay 402 also closes a circuit in parallel 50 with the circuit for relay 400 extending over brush 405 and the normal terminal of the bank of monitor switch 450 with which it is associated, to battery, through the winding of relay 403 and to battery through the inner 55 right normal contacts and winding of relay 404. With relays 403 and 404 both energized in this circuit, a circuit is established for relay 406 which may be traced from battery, through the winding of this relay, 60 the brush 407 and normal terminal of the bank with which it is associated, the right contact of relay 403 to ground at the outer left front contact of relay 404. Relay 406 energizes closing a circuit from ground, 65 through the outer left front contact of relay 404, the right contact of relay 403, the brush 407, inner left contact of relay 406, to battery, through the back contact and winding of stepping magnet 408. The stepping magnet 408 thereupon energizes advancing the 70 brushes of the switch 450 from their normal position terminals, whereupon the circuit of relay 406 is opened at brush 407 and relay 406 deenergizes opening the circuit of magnet 408 arresting the movement of the switch. 75

Upon the energization of relays 404 and 403, a circuit was also established from ground over the outer left front contact of relay 404, the right contact of relay 403, the inner left contact of relay 404, conductor 80 409, brush 328, the lower right and upper left contacts of cam 329, the intermediate back contact of relay 330, terminal 231, brush 298 of line switch 250, the outer left contact of relay 214, the outer left contact of relay 228 to battery through the winding of relay 227. With relay 227 energized, a circuit is established for relay 126 which may be traced from battery, through the winding of relay 126, conductor 141, the outer left contact of relay 227 to ground at the inner left contact of relay 211. Relay 126 energizes in this circuit, disconnecting the negative pole of high voltage battery 137 from the circuit previously traced, through 90 relays 124 and 130, connecting in place thereof the positive pole of battery 138. Current now flows through the winding of relay 130 in such a direction as to cause its energization, whereupon resistance element 181 is connected to the sleeve contact of jack 121 in parallel with the windings of relays 101 and 100, thereby reducing the resistance of the sleeve circuit to such an extent as to cause marginal relay 103 in the operator's 100 cord circuit to operate and complete the circuit of supervisory lamp 106. Lamp 106 thereupon illuminates. The illumination of lamp 106 at this time indicates to the operator that she may proceed to dial. The 110 reduction of the resistance in the sleeve circuit does not affect relay 101 which remains operated.

At the time relay 404 of the sender energized, it locked itself up, the circuit extending through its winding, its inner right front contact to ground at the left contact of relay 402, which circuit maintains relay 404 energized after switch 405 leaves position 1 and opens the initial energizing circuit of relays 404 and 403. Relay 403, however, deenergizes as soon following the advance of switch 450 to position 1 as its slow releasing characteristic permits and, therefore, the circuit previously traced for producing a 120 dial signal at the operator's position 125 is now maintained over brush 405 and the left contact of relay 402.

At the time the sender was seized and the 130 district sequence switch advanced into posi-

tion 3, a dialing circuit was established extending from battery, through the winding of the impulse relay 410 of the sender, over conductor 411, brush 331, the left contacts 5 of cam 332, the lower back contact of relay 330, terminal 232, brush 245, the intermediate left contact of relay 214, the inner left contact of relay 228, conductor 140, the left front contact of relay 119, the back contact 10 of relay 123 to ground at the contact of relay 124. Relay 410 energizes in this circuit. To insure that relay 410, upon being energized, is not disturbed during the period immediately elapsing after the seizure of the 15 sender due to disturbances in the toll line, relay 410 is held energized in a local circuit extending through its winding, the right winding of relay 412 and to ground at the left contact of relay 403. This local circuit 20 is, however, opened as soon as the dialing signal is initiated and relay 403 becomes de-energized. Upon the energization of relay 410, an obvious circuit is prepared for the slow releasing relay 413. Relay 413 in turn 25 prepares an obvious circuit for relay 414. With relays 413 and 414 both energized, the stepping magnet 417 of the first code register is placed under the control of the impulse relay 410.

30 In response to the illumination of lamp 106, the operator at position 125 actuates the dial key 105, thereby removing the supervisory equipment of the cord circuit from the sleeve conductor thereof and causing 35 lamp 106 to be extinguished. Relay 101 is now maintained operated from battery associated with the dial 107.

The operator now actuates the dial 107 in accordance with the first digit of the number of the desired line, this digit being the first code letter of the office designation. Relay 101 now follows the interruptions of the dial contacts to intermittently connect and disconnect ground from the composite 40 leg of the toll line 150, whereupon relay 124 is intermittently energized and deenergized. The intermittent operation of relay 124 causes ground to be intermittently applied to the conductor 140, the circuit extending 45 from ground at the contact of relay 124, the back contact of relay 123, the left front contact of relay 119, conductor 140, the inner 50 left contact of relay 228, the intermediate left contact of relay 214, conductor 201, brush 245, terminal 232, the lower back contact of relay 330, the left contacts of cam 332, brush 331, conductor 411 to battery, through the winding of impulse relay 410. This impulse relay thereupon follows the 55 interruptions of the dial contacts and effects the setting of the "A" code register.

Upon the first deenergization of relay 410, a circuit is established from ground at its back contact over the left front contact of 60 relay 413, winding of relay 415, brush 416 of the steering switch and the normal terminal upon which it is standing, the contact and winding of stepping magnet 417 to battery, through the left winding of off-normal relay 418. Magnet 417 and off-normal 65 relay 418 energize in this circuit, relay 418 connecting ground over its contact to the off-normal conductor 432 for holding the relays 400 and 404 energized independently of relay 402. Relay 415 also energizes in the 70 circuit of magnet 417 and at its armature and front contact closes a circuit through the magnet winding 421 of the steering switch 425 preparatory to advancing the steering switch upon the termination of the first 75 series of impulses. A second circuit is also established at this time for relay 420 which may be traced from battery, the winding of relay 420, the inner right contact of relay 80 414, brush 419 and the normal terminal upon which it is standing, the armature and back contact of magnet 417, the normal terminal and brush 416 of switch 425, thence as traced, through the winding of relay 415 to ground at the back contact of relay 410. Relay 420 85 energizes in this circuit and at its right contact connects ground directly to the winding of relay 413 to insure that that relay will remain energized until the stepping magnet 417 90 has completed its stroke. At its left contact, relay 420 locks up and connects ground to one terminal of relay 415 for maintaining the relay 415, energized irrespective of the continued deenergization of relay 410. As soon as magnet 417 completes its forward 95 stroke, the circuit of relay 420 is opened and the holding circuits of relay 413 and relay 415 are opened. Thus, the complete energization of magnet 417 is insured regardless 100 of the period that relay 410 remains de-energized. When the stepping magnet 410 again energizes, the circuit previously traced for relay 415 and magnet 417 is opened and magnet 417 deenergizes, advancing the first 105 code register one step. Stepping relay 415, 110 however, being slow to release does not have time to retract its armature during the brief periods during which relay 410 is de-energized. Thus, in response to each de-energization and energization of relay 410, magnet 417 advances the "A" code register 115 one step.

Upon the termination of the first series of impulses, relay 410 remains energized for a sufficient time to permit relay 415 to retract 120 its armature, whereupon the circuit of magnet 421 of the steering switch is opened and the steering switch advances its brushes one step. With the steering switch in position 1, magnet 422 is operated in response to the operation of impulse relay 410 for advancing the brushes of the "B" code register to positions corresponding to the digit value of the second code digit dialed. Following the dialing 125 of the code digits of the desired line, the toll 130

operator dials the numerical digits, whereupon the numerical registers, not shown, of the sender are operated to register the numerical designations of the desired line. Following the registration of the complete line designation, the translator switch, not shown, is set in accordance with the combined settings of the A and B registers in the manner fully set forth in the patent to O. H. Kopp hereinbefore referred to, and the circuits of the sender are prepared for controlling the setting of automatic switches to extend the connection to the terminals of the desired line. In the preparation of the sender circuits, the sequence switch thereof, cams of which are illustrated in the upper portion of Fig. 4, is advanced out of its normal position 1 into position 2 preparatory to controlling the setting of the district selector 350 in its brush selection movement.

It will be recalled that the sequence switch 310 of the district selector 350 was advanced to position 3 following the selection of the sender and, therefore, with the sequence switch of the sender in position 2, a fundamental switch controlling circuit is established between the circuits of the district selector 350 and the sender which may be traced from battery through the right winding of relay 307, the lower contacts of cam 333, contact 356 of relay 318, brush 327, the right back contact of advance relay 401, the windings of the sender stepping relay 430, the back contact of relay 428, contact of cam 427, winding of polarized overflow relay 424 to ground through the left contacts of cam 426. Relays 307 and 430 energize in this circuit but relay 424 being polarized does not receive current of the right polarity to cause its operation. Relay 430 upon energizing closes a circuit, not shown, in the well-known manner for associating a proper pair of counting relays with contacts of the translator switch for controlling district brush selection.

At the district selector, relay 307 upon energizing closes a circuit for advancing sequence switch 310 out of position 3 into position 4, which circuit may be traced from battery, through the magnet winding of the sequence switch, the upper left contact of cam 324, the outer left front contact of relay 307 to ground at the right contact of cam 308. As soon as the sequence switch advances out of position 3, the initial energizing circuit of relay 307 previously traced is opened at the lower left contact of cam 333, but relay 307 is maintained energized in series with the stepping relay 430 over a circuit which may now be traced from battery, through the right winding and right front contact of relay 307, the upper left and lower right contacts of cam 333, and thence over the circuit traced to ground, at the lower left contact of cam 426. With relay 307 energized and sequence switch 310 in

position 4, a circuit is established for the up-drive magnet 334 of the switch 350 for advancing the switch shaft in its brush selecting movement. This circuit may be traced from battery, through the winding of magnet 334, the lower right contact of cam 335, the outer left front contact or relay 307 to ground at the right contact of cam 308. As the switch shaft advances in its brush selection movement, the commutator brush 338 engages segments of commutator strip 337, whereupon a circuit is intermittently established in shunt of the windings of stepping relay 430 which may be traced from battery, through the right winding of relay 307, right front contact of this relay, the upper left contact of cam 333, the upper right contact of cam 336, commutator strip 337, brush 338 to ground, at the upper left contact of cam 339. Relay 307 is maintained energized over this shunt but relay 430 deenergizes each time that the brush 338 engages a conducting portion of the strip 337 corresponding to a brush tripping position.

In response to the intermittent operation of relay 430, counting relays of the sender operate successively in pairs in the well-known manner until the 0' counting relay 431 energizes in parallel with relay 428, the operated counting relays locking to ground over the contacts of cam 429. With relays 431 and 428 energized, relay 428 opens the fundamental switch controlling circuit previously traced and relay 431 establishes a circuit in a well-known manner for advancing the sender sequence switch out of position 2 into position 4. As soon as the sequence switch leaves position 2, the operated counting relays are released through the opening of the contacts of cam 429. The circuits of the sender are now in condition for controlling the group selection movement of the district selector 350.

At the district selector, upon the opening of the fundamental circuit, relay 307 deenergizes as soon as the brush 338 engages the next insulating segment of the commutator strip 337 and at its outer left back contact establishes a circuit for advancing sequence switch 310 out of position 4 into position 5. This circuit may be traced from battery, through the magnet winding of sequence switch 310, the lower left contact of cam 324, the outer left back contact of relay 307 to ground at the right contact of cam 308. With the sequence switch in position 4 and sequence switch 310 of the district selector in position 5, the previously traced fundamental switch controlling circuit is again established through the windings of sender stepping relay 430 and the right winding of relay 307. Relay 307 again energizes, closing the previously traced locking circuit for itself over the upper left and lower right contacts of cam 333 and advances sequence

switch 310 into position 6. As sequence switch 310 advances from position 5 into position 6, an obvious circuit is closed for the trip magnet 343, extending over the lower right contact of cam 339 for energizing the trip magnet 343 for tripping the selected set of brushes upon the next subsequent upward movement of the switch shaft.

With sequence switch 310 in position 6 and relay 307 energized, the previously traced circuit for the up-drive magnet 334 is again established and the switch shaft is driven upwardly. During the first portion of this upward movement, the selected set of brushes is tripped through the operation of magnet 343 in the well-known manner, and thereafter the tripped set of brushes advances in contact with the terminals of its associated bank. During the continued upward movement of the switch shaft, the brush 341 engages the commutator strip 340 for intermittently shunting the stepping relay 430 of the sender each time that the selected set of brushes approaches the bottom of the groups of bank terminals. This shunt circuit may be traced from battery, through the right winding and right front contact of relay 307, the upper contacts of cam 333, commutator strip 340, brush 341 to ground at the upper left contact of cam 339. Relay 307 is maintained energized over this shunt path but relay 340 deenergizes each time that the brush 341 encounters a conducting portion of the strip 340 and in the well-known manner causes the successive energization of pairs of counting relays. The operated counting relays are again locked over the contact of cam 429. As soon as the district brush shaft has advanced to such a position as will satisfy the district group registration of the sender, the 0' counting relay 431 energizes in parallel with relay 428, the relay 431 advancing the sender sequence switch into position 6, releasing the operated counting relays and preparing the circuits of the sender for incoming brush selection, and relay 428 opening the fundamental switch controlling circuit previously traced.

As soon following the opening of the fundamental circuit as the brush 341 engages the next insulating segment of commutator strip 340, relay 307 deenergizes opening the circuit of the up-drive magnet 334 and closing the previously traced circuit for advancing the sequence switch 310 out of position 6 into position 7. The selected set of brushes has now been positioned in engagement with the lowermost set of terminals in a desired group of its bank.

With sequence switch 310 in position 7, relay 307 is energized in a circuit which may be traced from battery through its left winding, the left contacts of cam 306 to ground at the inner right contact of relay 303 and at its outer left front contact closes

the previously traced circuit for advancing sequence switch 310 out of position 7 into position 8. As the sequence switch leaves position 7½, the previously traced operating circuit of relay 307 is opened at the upper left contact of cam 306 but if, however, the trunk terminating in the first set of terminals, upon which the brushes are resting, is at the time busy, as will be assumed, relay 307 remains energized over a locking circuit which may be traced from battery through its right winding and inner left contact, the lower contacts of cam 309, overflow segment 349, wiper 351, test brush 342 to ground on the test terminal of such first busy trunk. When, therefore, sequence switch 310 reaches position 8, since relay 307 is energized, the previously traced circuit of the up-drive magnet 334 is established and the switch shaft is driven upwardly in a trunk hunting movement. As long as the brush 342 encounters busy ground potential on the test terminals of the trunks over which it passes, relay 307 will be maintained energized and the circuit of the up-drive magnet will remain closed. When, however, the first idle trunk is encountered, having no ground potential upon the test terminal thereof, the locking circuit of relay 307 is destroyed and relay 307 thereupon deenergizes opening the circuit of up-drive magnet 334 and closing the previously traced circuit for advancing sequence switch 310 out of position 8 into position 9.

As soon as relay 307 deenergizes, busy ground potential is connected over the test brush 342 to the test terminal of the selected trunk over the brush 351, the overflow strip 349 of the commutator, the lower contacts of cam 309, the right back contact of relay 307 to ground at the upper left contact of cam 357. After sequence switch 310 reaches position 8½, ground potential is connected to the brush 342 over brush 351 and strip 349 and the left contacts of cam 309 independently of relay 307.

As soon as the sequence switch reaches position 9, a circuit is established for reenergizing relay 307, which circuit extends from battery, through the left winding of relay 307, the lower contacts of cam 306, the right contact of relay 302, this relay having energized, as will be recalled, immediately upon the seizure of the sender, thence over the innermost lower back contact of relay 353 to ground at the upper right contact of cam 339. As soon as relay 307 energizes, the previously traced circuit is established for advancing sequence switch 310 into position 10, in which position the fundamental switch controlling circuit is extended from the sender to the control relay of the selected incoming selector 650. This circuit may be traced from battery, through the

left winding of relay 605, the upper contacts of cam 609, the lower right contact of cam 615, the upper left contact of cam 603, conductors 504 and 501, brush 345, the upper- 5 most back contact of relay 353, the upper right and lower left contacts of cam 354, contact 356 of relay 318, brush 327, the right back contact of advance relay 401, the windings of sender stepping relay 430, the 10 back contact of relay 428, contact of cam 427 and winding of overflow relay 424, the upper left and lower right contacts of cam 426, brush 326, the next to outer right contact of relay 318, the lower left and upper 15 right contacts of cam 355, the lower back contact of relay 353, brush 346, conductors 502 and 505 to ground, through the lower contacts of cam 607. Relays 605 and 430 energize in this circuit, polarized relay 424 20 not receiving current in the proper direction to cause its energization. Relay 430 upon energizing prepares a circuit in the well-known manner from the thousands register of the sender to the counting relays for 25 controlling the incoming selector 650 in its brush selection movement.

Relay 605 upon energizing completes a circuit from ground at its right front contact through the lower left contact of cam 30 612, to battery through the magnet winding of sequence switch 610 for advancing the sequence switch out of position 1 and into position 2, where a circuit is closed for the up-drive magnet 618. This circuit may be 35 traced from battery, through the winding of magnet 618, the lower right contact of cam 612 to ground at the right front contact of relay 605. In position 2 of sequence switch 610, relay 605 is maintained energized in a circuit from battery through its 40 left front contact and the lower right contact of cam 615, thence over the fundamental circuit ground at cam 607 as described.

The up-drive magnet 618 causes the brush 45 shaft of the selector to move upwardly and for each brush tripping position passed over to close a circuit for shunting the sender stepping relay 430 while maintaining relay 605 operated. This circuit may 50 be traced from battery, through the left winding and left front contact of relay 605, lower contacts of cam 615, commutator strip 630, brush 628, to ground at the lower left contact of cam 613. The stepping relay 430 55 is deenergized each time the above traced shunt circuit is closed and counting relays of the sender are operated. This operation continues until the 0' counting relay 431 energizes in parallel with relay 428 when 60 the sender sequence switch is advanced out of position 6 into position 8, unlocking the counting relays and preparing the sender circuits for incoming group selection, and the fundamental circuit is opened. As soon 65 following the opening of the fundamental

circuit as the brush 628 encounters the next insulating portion of commutator strip 630, the circuit for relay 605 is opened and relay 605 deenergizes opening the circuit of the up-drive magnet 618. Relay 605 also closes 70 a circuit from ground through its right back contact, lower left contact of cam 611 to battery, through the winding of sequence switch magnet 610 for driving said sequence switch out of position 2 into position 3. 75

In position 3 of sequence switch 610, and position 8 of the sender sequence switch, the fundamental circuit last traced is again closed in the manner described and relays 430 and 605 again energize, relay 430 preparing a circuit from the hundreds and thousands numerical registers of the sender to the counting relays in the well-known manner. Relay 605 upon energizing again closes the previously traced circuit over its 80 right front contact for advancing sequence switch 610 into position 4, relay 605 being maintained energized over the fundamental circuit in position 4 of the sequence switch in the manner previously described and completing the circuit previously traced for the up-drive magnet 618, driving the switch shaft upwardly in its group selecting movement. As the sequence switch 610 passed through position 3 into position 4, a circuit 85 was closed at the lower contacts of cam 614 for the trip magnet 619 so that, during the initial portion of the group selecting movement of the switch shaft, a set of brushes will be tripped into engagement with the 90 multiple terminals of the bank associated therewith. For each group of terminals traversed by the tripped set of brushes, a circuit is closed from battery, through the left winding and left front contact of relay 100 605, the lower right contact of cam 615, the upper right contact of cam 606, commutator strip 631, brush 627 to ground at the lower left contact of cam 613. The closure of this circuit holds relay 605 energized and shunts 105 the stepping relay 430 of the sender.

When the sender has become satisfied, the 0' counting relay 431 energizes in parallel with relay 428, the relay 431 advancing the sender sequence switch out of position 8 110 into position 10, unlocking the operated counting relays and preparing the sender circuits for controlling the final brush selection, and relay 428 opening the fundamental circuit. As soon following the opening of 115 the fundamental circuit as the brush 627 encounters the next insulating portion of commutator strip 631, relay 605 deenergizes opening the circuit of the up-drive magnet 618 and completing a circuit from ground at 120 its right back contact over the lower left contact of cam 611 for advancing sequence switch 610 into position 5. The selected set of brushes 621, 622 and 623 have now been 125 positioned in engagement with the lower- 130

most set of terminals of its associated bank.

In position 5 of sequence switch 610 a circuit is closed from battery, through the right winding of relay 605 to ground 5 through the right contacts of cam 634. Relay 605 operates and locks in the following circuit provided the first trunk in the group, upon the terminals of which the brushes 621, 622 and 623 are outstanding, is busy.

- 10 This circuit extends from battery through the left winding and left front contact of relay 605, upper contacts of cam 614, brush 623 to the grounded test terminal of the busy trunk. Relay 605 at its right front contact closes a circuit over the lower left contact of cam 612 to drive sequence switch 610 into position 6. Relay 605 remains energized in this position and completes a circuit from its right front contact, the lower right contact of cam 612 to battery through the winding of up-drive magnet 618. The brush shaft is driven upward to move the brushes 621, 622 and 623 over the terminals of the group in search of an idle trunk. When 25 the first idle trunk is reached, no ground potential is present upon the test terminal thereof and the holding circuit of relay 605 is opened. This relay, however, remains energized for an instant by means of a circuit from battery through the right winding of said relay, lower right and upper left contacts of cam 634, commutator strip 632, brush 629, the upper contact of cam 613 to ground at the right front contact of relay 30 35 605 to insure that the movement of the brush shaft will continue until the brushes are properly centered upon the terminals of the idle trunk. When the brush 629 engages the next insulating segment of strip 632, relay 605 is deenergized and the circuit of magnet 618 is opened causing the brush shaft to cease its upward movement. Relay 605 at its right back contact closes a circuit extending over the lower left contact of cam 40 45 611 for advancing sequence switch 610 out of position 6 into position 7.

In position 7 of sequence switch 610, a circuit is closed from battery, through the left winding of relay 605, upper contacts of cam 609, lower contact of cam 616, brush 622, trunk conductor 625, upper left and lower right contacts of cam 705 to ground at the lower left contact of cam 706. Relay 605 becomes energized and closes the circuit 50 55 through its right front contact for driving sequence switch 610 out of position 7 into position 8. While sequence switch 610 is moving out of position 7 and into position 8, relay 605 is maintained energized over its left winding and left front contact, lower contact of cam 616 to ground as traced.

The trunk 624 and 625 selected by the incoming switch is held busy so as to be 60 65 non-selectable by other switches by means

of ground potential placed on the test conductor 626, over a circuit extending from ground, through the right contacts of cam 614, test brush 623, and thence to the multiple terminals of the test conductor 626.

The fundamental switch controlling circuit for controlling the selecting movements of the final selector switch 750 is now completed and may be traced from battery through the right winding of relay 700, 75 the lower left contact of cam 703, the lower left contact of cam 702, conductor 624, brush 621, the right contact of cam 617, conductors 504 and 501, thence as traced through the sender returning over conductors 502 and 505, the upper contact of cam 612 to ground at the right front contact of relay 605. Relay 700 energizes and closes a circuit for relay 721 which may be traced from battery through the left winding of this relay, upper left contact of cam 707, left front contact of relay 700 to ground at the upper contact of cam 708. Relay 721 energizes in this circuit and at its left front contact closes a locking circuit for itself 80 extending from battery through its left winding, back contact of relay 724, left front contact of relay 721 to ground on conductor 626. Relay 721 upon energizing closes a circuit extending from ground at 85 its right front contact over the lower contacts of cam 709 to battery through the magnet winding of sequence switch 710 for advancing sequence switch 710 into position 90 95 2. When sequence switch 710 moves out of position 1, the initial energizing circuit of relay 700 is opened at the lower contact of cam 703, the relay 700 remaining energized over the fundamental circuit by reason of a locking circuit extending from battery, through its right winding, lower contact of cam 740, the right contact of relay 700, the lower right contact of cam 703, thence to ground over the fundamental circuit as previously traced. Relay 700 upon energizing, with sequence switch 710 in position 2, 100 105 closes a circuit for the high speed up-drive magnet 726, extending from battery, through the winding of magnet 726, the upper right contact of cam 711, the left front contact of relay 700 to ground at the upper contact of cam 708. Magnet 726 upon energizing advances the switch shaft of the final selector in its brush selection movement.

As the switch shaft approaches each brush selection position, the brush 736 engages a conducting portion of commutator strip 730, thereby establishing a shunt around the windings of stepping relay 430 of the sender while maintaining relay 700 energized. This shunt circuit may be traced from battery through the right winding of relay 700, the lower contact of cam 740, the right front contact of relay 700, the lower right contact of cam 703, the upper right 110 115 120 125 130

contact of cam 702, commutator strip 730, brush 736, the right contact of cam 707, the left front contact of relay 700 to ground at the upper contact of cam 708. As soon as the sender is satisfied with respect to its final brush registration, the sender sequence switch advances as previously described and the fundamental circuit is opened. As soon after the opening of the fundamental circuit as brush 736 engages the next insulating portion of commutator strip 730, the holding circuit of relay 700 is opened and relay 700 deenergizes. As soon as relay 700 retracts its armature, the circuit of the up-drive magnet 726 is opened and a circuit is established from ground at the upper contact of cam 708, the left back contact of relay 700, the lower right contact of cam 712 to battery through the magnet winding of sequence switch 710 for advancing the sequence switch 710 into position 3. With the sequence switch in position 3, a circuit is closed from ground at the lower right contact of cam 706, through the winding of trip magnet 735 for rotating the trip spindle preparatory to tripping the selected set of brushes.

When sequence switch 710 reaches position 3, the energizing circuit of relay 700 and of the stepping relay 430 of the sender is again established. Relay 700 again establishes the previously traced circuit for advancing sequence switch 710 out of position 3 into position 4. In position 4, the circuit of the up-drive magnet 726 is again established as previously traced for advancing the switch shaft in its group or tens selection movement. As the switch shaft advances through the initial portion of its group selection movement, the selected set of brushes is tripped in the well-known manner. As the switch shaft approaches its first group selection position, the brush 738 engages the lowermost conducting portion of the commutator strip 737 and a circuit is closed in shunt of the stepping relay of the sender and may be traced from battery through the right winding of relay 700, the lower contact of cam 740, the right front contact of relay 700, the right contacts of cam 703, commutator strip 737, brush 738, and thence as traced to ground at the upper contact of cam 708. As the switch shaft advances, the sender stepping relay is intermittently shunted until the sender is satisfied with respect to the setting of its tens register when the sequence switch of the sender is advanced and the fundamental circuit is opened in the well-known manner. As soon, thereafter, as the brush 738 engages the next insulating portion of the commutator strip 737, relay 700 deenergizes opening the circuit of the up-drive magnet 726 and closing the previously traced circuit over the lower

right contact of cam 712 for advancing sequence switch 710 into position 5.

In position 5, the fundamental circuit is again established and relay 700 energizes advancing sequence switch 710 into position 6. With relay 700 energized and sequence switch 710 in position 6, a circuit is established for the low speed up-drive magnet 739, extending from battery through the winding of this magnet, the lower left contact of cam 707, the left front contact of relay 700 to ground at the upper contact of cam 708. Magnet 739, upon energizing, advances the switch shaft in its units selection movement. During this movement of the switch shaft, an intermittent shunt is established which may be traced from battery, through the right winding of relay 700, the lower contact of cam 740, the right front contact of relay 700, the lower right contact of cam 703, the upper right contact of cam 702, commutator strip 730, brush 736, thence as traced to ground at the upper contact of cam 708. Relay 700 is maintained energized in this shunt circuit but the sender stepping relay is intermittently deenergized until the sender is satisfied with respect to its units registration when the fundamental circuit is opened at the sender. As soon thereafter as the brush 736 engages the next insulated portion of commutator strip 730, relay 700 deenergizes, opening the circuit of the up-drive magnet 731 and closing the previously traced circuit for driving the sequence switch 710 out of position 6 and into position 9.

The brushes 752, 753 and 742 are now positioned upon the terminals of the desired line and the final selector thereupon proceeds in the usual manner to test the line for its busy or idle condition. Assuming that the line is found to be idle, the sequence switch 710 is advanced through intermediate positions from the position 9 into the talking position 15, in which position the talking circuit is extended from conductors 624 and 625 over the lower contacts of cam 702, the upper contacts of cam 705, and brushes 752 and 753 to the conductors of the called line.

When sequence switch 710 leaves position 8½ the circuit hereinbefore traced for relay 605 is opened at the lower left contact of cam 706 and relay 605 thereupon deenergizes. Relay 605 upon deenergizing closes a circuit from ground at its right back contact over the lower left contact of cam 611 for advancing sequence switch 610 out of position 8 into position 9. With sequence switch 610 in position 9, relay 605 is connected in a circuit extending from battery, through its left winding, the right contacts of cam 609, conductors 505 and 502, thence as traced to the sender, through the windings of sender stepping relay 430 and the

winding of polarized relay 424, returning over conductors 501 and 504, the upper left contact of cam 606 to ground at the upper left contact of cam 615. Relays 605, 430 and 424 energize in this circuit, as the current now flows in the proper direction to energize the polarized relay 424. Relay 605 upon energizing closes a circuit over its right front contact for advancing sequence switch 610 from position 9 into position 11. As the sequence switch is passing from position 9 into position 11, relay 637 is energized over the lower contact of cam 641 for the purpose of opening the ringing control circuit and to disconnect ground from the tip conductor 504 of the trunk circuit. Upon reaching position 11 relay 605 is energized from ground on conductor 503, over cam 608, the lower left and upper right contacts of cam 609 to battery through the left winding of relay 605. Relay 605 upon energizing locks over its left armature to ground through the upper left and lower right contacts of cam 614 and advances sequence switch 610 into position 13. After the sequence switch leaves position 11½, relay 605 is maintained locked over its left contact and the left contacts of cam 609.

At the sender, upon the operation of the polarized relay 424, an obvious circuit is closed for relay 401 which opens the fundamental circuit and at its left contact opens the shunt around the right winding of relay 402. The current now flowing through the windings of relay 402 over the circuit previously traced to battery through the winding of marginal relay 302 is now decreased to such an extent that relay 302 deenergizes opening the holding circuit of relay 307 extending through the right front contact of relay 302, whereupon relay 307 deenergizes. With relay 307 deenergized, a circuit is now closed for advancing sequence switch 310 out of position 10 into position 11, which circuit may be traced from battery through the winding of sequence switch magnet 310, the lower left contact of cam 324, the outer left back contact of relay 307 to ground at the right contact of cam 308. With sequence switch 310 in position 11, a circuit is established for the relay 330 extending from battery, through the lower winding of this relay, the upper right and lower left contacts of cam 358 to ground, through the left front contact of relay 318, thus opening the tip and ring leads of the district link and disconnecting the winding of supervisory relay 359 during the talking selection operation of the district selector 350.

A circuit is also established at this time for relay 307 which may be traced from battery, through its right winding, the lower contacts of cam 333, contact 356 of relay 318, brush 327, the back contact of relay 401, winding of stepping relay 430, the back

contact of relay 428, the contact of cam 427, now closed in position 16, the winding of relay 424 to ground, over the left contacts of cam 426. Relays 307 and 430 energize in this circuit, relay 307 closing a circuit over the upper left contact of cam 324, the outer left front contact of relay 307 to ground at the right contact of cam 308 for advancing sequence switch 310 out of position 11. After sequence switch 310 leaves position 11, its driving circuit is maintained closed over the upper left contact of cam 308 to the inner right front contact of relay 303 to insure its continued movement through successive talking selection positions. As the sequence switch continues to rotate, an intermittent shunt is placed around the windings of sender stepping relay 430, extending from battery, through the right winding and right front contact of relay 307 to ground, through the lower right and upper left contacts of cam 309. Relay 307 is maintained energized over the shunt path but stepping relay 430 of the sender intermittently deenergizes, successively operating pairs of counting relays at the sender in accordance with the talking selection registration of the translator switch of the sender. When the sender is satisfied with respect to its talking selection registration, the fundamental circuit is opened through the operation of relay 428 in the well-known manner and the circuit of relay 307 is opened. Upon the deenergization of relay 307, the circuit of sequence switch magnet 310 is opened and the sequence switch comes to rest in one of the talking selection positions 12, 14 or 16. It having been assumed that the connection has been established to a full automatic office, the fundamental circuit is opened by the sender when the sequence switch is passing through position 13½, and therefore the sequence switch 310 is arrested in position 14. Relay 307 upon deenergizing also closes a circuit extending from the left terminal of the winding of relay 318 over the uppermost front contact of relay 330, the left contacts of cam 360, the outer left back contact of relay 307, the upper left contact of cam 308 to ground at the inner right contact of relay 303, thereby shunting relay 318 and causing its deenergization. With relay 318 deenergized, the circuit previously traced through the windings of relay 402 and the windings of relays 302 and 323 is opened causing the release of relay 402.

When sequence switch 310 advances beyond position 10, the circuit previously traced for relay 410 is opened at the left contacts of cam 332 and relay 410 thereupon releases, in turn releasing relays 413 and 414. Relay 413 upon deenergizing establishes a circuit from ground at its right normal contact over brush 435, and the terminals of

the restoring bank of the steering switch 425, back contact and winding of stepping magnet 421 to battery through the right winding of relay 418. Magnet 421 operates in this circuit advancing the brushes of the steering switch to their normal positions, the circuit of magnet 421 being interrupted at brush 425 when the brush 435 reaches normal. Relay 414 upon deenergizing establishes a circuit for the stepping magnet 417 of the "A" register, which may be traced from battery, through the left winding of relay 418, the winding and contact of magnet 417, terminals of the restoring bank and brush 433 of the register to ground at the outer right back contact of relay 414. The magnet 417 advances the brushes of the register to normal position in which position the brush 433 extends the restoring circuit through brush 434 of the "B" register and through the winding of magnet 422 to battery. The magnet 422 energizes in this extended restoring circuit, restoring the brushes of the "B" register to normal. In a similar manner the remaining registers of the sender are restored to normal.

Upon the deenergization of relay 402, and the removal of ground from the off-normal conductor 432 of the sender, the holding circuit of relay 404 is opened. This relay deenergizes, closing a circuit for relay 406 which may be traced from battery through the winding of this relay, brush 407 and the off-normal terminals of the bank with which it is associated, to ground at the outer left back contact of relay 404. In response to the energization of relay 406, a circuit is established from battery, through the winding and back contact of stepping magnet 408 of the monitor switch 450, the inner left contact of relay 406, and thence to ground over brush 407 and the outer left back contact of relay 404. Magnet 408 energizing in this circuit, advances the brushes of the monitor switch from whatever position they are standing in at the time into their normal position. Upon reaching normal the circuits of relay 406 and magnet 408 are opened. The deenergization of relay 402 also closes circuits, not shown, for restoring the remaining apparatus of the sender to normal. Since, however, the manner in which this is accomplished does not intimately concern this invention, these restoring operations will not be further disclosed or described herein.

Upon the advance of sequence switch 310 of the district selector into position 14, relay 330 is held energized in a holding circuit extending from battery, through its lower winding, the upper contacts of cam 358, the lower front contact of relay 330, terminal 232, brush 245, the middle left contact of relay 214, the inner left contact of relay 228, conductor 140, the left front

contact of relay 119, the back contact of relay 123 to ground at the contact of relay 124. Thus, relay 330 is maintained energized until the toll operator receives a trunk closure signal, as will hereinafter be described.

A circuit is now established for the supervisory relay 359 of the district selector circuit which may be traced from battery, through the right winding of coil 600 at the incoming selector of Fig. 6, the outer contact of relay 601, lower left winding of repeating coil 639, the upper contacts of cam 607, conductors 505 and 502, brush 346, the lowermost contact of relay 353, the upper contacts of cam 355, winding of relay 359, the upper contacts of cam 354, the uppermost back contact of relay 353, brush 345, conductors 501 and 504, the lower contacts of cam 606, the upper left winding of repeating coil 639, the inner contact of relay 601, the left winding of coil 600, to ground at the outer right contact of relay 637. Relay 359 energizes in this circuit and as soon as interrupter 361 makes its right contact establishes a circuit for relay 362. This circuit may be traced from battery, through the winding of relay 362, the contact of relay 359, the right contact of interrupter 361, to ground over the upper contacts of cam 309. Relay 362 upon energizing locks over its inner right contact to ground at the right contact of cam 316 and establishes a circuit for relay 228 which may be traced from battery, through the winding of relay 228, the outer right back contact thereof, the middle right contact of relay 214, brush 238, terminal 229, the outer right contact of relay 362, to ground, at the left back contact of relay 318.

Relay 228 upon energizing in this circuit locks over its outer right front contact to ground at the inner right front contact of relay 214 and at its left contacts opens the connection heretofore existing over brush 298 through the winding of relay 227, and over brush 245 to ground at the front contact of relay 124. The removal of the ground connection from brush 245 destroys the holding circuit of relay 330 which thereupon releases, cutting the talking conductors of the district link through to the back contacts of the ringing relay 353. Relay 228 also establishes a circuit for the relay 117 extending from battery through the winding and back contact of this relay, thence over conductor 142, the inner right contact of relay 228 to ground at the inner left contact of relay 211. Relay 117 energizing in this circuit locks itself directly to ground on conductor 139 and at its right front contacts connects the talking conductors 200 and 201 to the tip and ring conductors of the toll line 150. Relay 227 at its outer right front contact also establishes a

circuit for the signaling relay 227 which may be traced from battery, through the winding of this relay and the outer right front contact of relay 228, the middle right contact of relay 214, brush 238, terminal 229, outer right contact of relay 362, thence to ground at the left back contact of relay 318. Relay 227 energizes in this circuit and establishes the previously traced circuit for relay 126, which again reverses the current flowing over the composite leg of the toll line 150 through the winding of polarized relay 130 causing relay 130 to respond and in the manner previously described, to cause the energization of marginal relay 103 and the lighting of the lamp 106. The lighting of lamp 106 at this time signals the toll operator that the talking connection has been put through and that the automatic ringing of the desired subscriber is proceeding.

When the interrupter 361 next makes its left contact, with relay 362 energized, a circuit is established for the ringing relay 353 which may be traced from battery, through the winding of relay 353, the outer left contact of relay 362, the left contact of interrupter 361, thence to ground through the upper contacts of cam 309. Relay 353 upon energizing establishes a ringing circuit extending to the incoming selector which may be traced from the source of ringing current 363, through lamp 371, contacts of cam 364, lower front contact of relay 353, brush 346, conductors 502 and 505, upper contacts of cam 607, lower left winding of repeating coil 639, condenser 640, ringing relay 602, upper left winding of repeating coil 639, lower contacts of cam 606, conductors 504 and 501, brush 345 to ground at the upper front contact of relay 353. Relay 353 also opens the talking circuit extending back to the toll line 150 and closes a circuit for relay 302 which may be traced from battery, through the winding of relay 302, the inner upper front contact of relay 353, the right contacts of cam 301, to ground at the left back contact of relay 318. Relay 302 operates in this circuit and locks over its left front contact through cam 301 to ground at the left back contact of relay 318. When the interrupter 361 next opens its left contact, the circuit for ringing relay 353 is opened, but relay 302 remains locked.

Relay 602 responds to the ringing current applied by relay 353 from the source 363 and establishes a circuit for relay 601 extending from battery, through the right winding of relay 601, the contact of relay 602, to ground at the inner right back contact of relay 637. Relay 601 upon energizing in this circuit removes the windings of coil 600 from the connection previously traced to the contacts of relay 353. A circuit is also established at this time for relay 642 which may be traced from ground, inner back contact of relay 637, contact of relay 602, back contact of relay 662, inner left normal contacts and winding of relay 642 to battery at the normal inner lower contact of relay 604.

Relay 642 energizes in the circuit traced locking itself directly to ground at its inner left front contact short circuits the lower right winding of repeating coil 639 through its outer left front contact, and establishes a circuit for pick-up relay 644. This latter circuit may be traced from battery, through the winding and inner left normal contacts of relay 644, right front contact of relay 642 to ground through the right contacts of cam 643. Relay 644 upon energizing locks over its inner left front contact, the back contact of relay 645, to ground at the inner back contact of relay 637 and also establishes a circuit from ground at its outer left contact to battery through the winding of ringing relay 604. Relay 604 upon energizing closes a circuit for alternately applying ringing current from source 649 to the called line. This circuit may be traced from the ringing source 649 through the interrupter 648 or battery, through the interrupter 647, over the right contact of cam 646, ringing cut-off relay 645, inner right front contact of relay 644, lower front contact of relay 604, upper contact of cam 616, brush 622, conductor 625, upper contacts of cam 705, brush 753, ring side of the called line, to ground through the bell 714 of the desired subscriber's station. Through the operation of interrupters 647 and 648, the bell 314 is operated in accordance with a one-ring code. During the application of ringing current, ringing relay 604 connects ground over its innermost upper front contact, the left contact of cam 617, brush 621, conductor 624, lower contacts of cam 702, brush 752, and thence to the tip side of the called line for shunting out the bells of the substations connected to the tip side of the line.

Immediately following the initiation of the ringing operation and the deenergization of relay 353, relay 602 deenergizes, releasing relay 601, which again connects the windings of coil 600 across the tip and ring conductors 501 and 502 of the trunk extending back to the district operator. Relay 359 is again energized, closing a circuit for relay 323 which may be traced from battery through the winding of relay 323, the upper contacts of cam 321, the right contact of relay 302, the innermost lower contact of relay 353, the contact of relay 359, the inner right contact of relay 362, to ground at the right contact of cam 316. Relay 323 energizes in this circuit and closes a circuit for advancing sequence switch 310 into the talking position 15. This circuit extends from battery through the winding of se-

quence switch magnet 310, the upper left contact of cam 324, the inner left contact of relay 323 to ground at the right contact of cam 357. As soon as the sequence switch 5 leaves position 14 relay 323 deenergizes and the circuit of sequence switch magnet 310 is opened. In position 15 relay 362 is maintained energized in a circuit extending from battery, through its winding, the contact of relay 359, to ground at the upper right contact of cam 339. Relay 302, however, releases as soon as the sequence switch leaves 10 position 14, since its holding circuit is opened at the lower right contact of cam 301.

15 Assume that the wanted subscriber recognizing the ringing signal as a call for his substation, removes his receiver from the switchhook. A circuit is thereupon established for cutting off the ringing current in 15 which relay 645 responds, opening at its armature and back contact the locking circuit for relay 644. Relay 644 thereupon de-energizes opening the circuit of relay 604, which disconnects the source of ringing current and connects the called line through to 20 the right windings of repeating coil 639. Relay 603 now becomes energized over a circuit extending from battery through the lower winding of this relay, the lower right 25 winding of repeating coil 639, the lowermost back contact of relay 604, thence as previously traced to the ring side of the called line through the substation, returning over the tip side of the line to the left contact of cam 617, thence through the innermost back 30 contact of relay 604, the upper right winding of repeating coil 639 to ground through the upper winding of relay 603. Relay 603 upon energizing closes an obvious circuit 35 through the left winding of relay 601 which again disconnects the windings of battery feed coil 600 from the conductors 501 and 502 of the trunk circuit. Relay 359 at the 40 district selector link now deenergizes opening the circuit of relay 362 which in turn opens the circuit of relay 227, and in the manner previously described, causes the extinguishing of the lamp 106 at the toll operator's position. The extinguishing of the 45 lamp 106 signals to the toll operator that the called subscriber has answered. The release of relay 362 also closes a circuit for again energizing relay 323, this circuit extending from battery, through the winding 50 of relay 323, the upper contacts of cam 321, the inner left back contact of relay 362, the upper contacts of cam 301, thence to ground at the left back contact of relay 318. Relay 323 now locks over its inner right contact to ground at the lower left contact of cam 389.

Had the called line been busy at the time the line was tested by the final selector switch 750, thence sequence switch 710 of 55 the final selector would have advanced into

position 17, in which position through the intermittent operation of relay 700 under the control of interrupter 715 an intermittent ground would have been connected to the ring side 625 of the trunk circuit extending back to the incoming selector 650. Thus, with the incoming selector in the talking position, relay 603 is intermittently operated in turn intermittently operating relay 601 to periodically connect and disconnect the windings of coil 600 across the conductors 501 and 502 of the trunk circuit extending to the district selector 350. In response to the periodic connection of coil 600, relay 359 is intermittently operated in turn 70 causing the intermittent operation of relays 362, 227 and 130. In this manner the lamp 106 at the toll operator's position is flashed to signal the operator that the wanted line is busy. 85

Release of the connection.

Upon the termination of conversation and the hanging up of the receiver at the called subscriber's station, relay 603 deenergizes 90 opening the circuit of relay 601, reconnecting the windings of coil 600 across the conductors 501 and 502 of the trunk circuit. Relay 359 responds in the circuit previously traced over the trunk circuit, in turn, operating relay 362 and causing the illumination of the lamp 106 at the toll operator's position in the manner previously described. The toll operator, noting the illumination of lamp 106, withdraws the 95 plug 120 from the jack 121, releasing relays 104 and 101. The release of relay 104 restores the cord circuit equipment to normal. Relay 101 in releasing opens up the composite leg of the toll line 150 thereby causing the release of relay 124. Relay 124 in releasing removes the ground from the conductor 140 thereby releasing relay 208 which, after an interval, releases and opens the circuit of relay 211. Relay 211 in re-100 tracting its outer right armature opens the locking circuit of relay 214 which relay thereupon releases. At its inner left contact relay 211 removes ground from conductor 139 releasing relays 119, 117 and 131, 105 whereupon these relays restore. Relay 131 in restoring disconnects ringing relay 118 from the composite leg of the toll line. 110

At the district selector 350 upon the de-energization of relay 214, relay 303 releases 115 closing a circuit from ground at its inner right back contact, over the right contacts of cam 320 to battery, through the winding of sequence switch magnet 310 for advancing the sequence switch into position 18. As the sequence switch leaves position 15, the locking circuit of the relay 323 is opened and this relay releases. With sequence switch 310 in position 18, a circuit is closed for down-drive magnet 365 extending from battery, through 120

the winding of magnet 365, the lower left and upper right contacts of cam 320 to ground at the inner right contact of relay 303. Through the operation of magnet 365, the switch shaft is driven downwardly into normal position, where brush 341 engages normal segment 366, closing a circuit for advancing sequence switch 310 into normal position. This circuit may be traced from battery, 5 through the magnet winding of sequence switch 310, the lower right contact of cam 324, segment 366, brush 341 to ground at the upper left contact of cam 339. When the sequence switch 310 leaves position 17, 10 ground is removed from the test brush 342 at the left contacts of cam 309 and the circuit, extending over conductors 503 and 507, contact of cam 608, left contacts of cam 609, through the left contact and winding of 15 relay 605, is opened. Relay 605 thereupon deenergizes closing a circuit extending from ground at its right back contact over the right contact of cam 641 to battery, through the winding of relay 637. Relay 637 energizes 20 closing a circuit extending from ground over its inner front contact, the lower right contact of cam 611 to battery, through the winding of sequence switch magnet 610 for advancing the sequence switch into position 18.

With sequence switch 610 in position 18, a circuit is established for the down-drive magnet 620 extending over the lower contacts of cam 613, and the switch shaft is 25 thereby driven downwardly into its normal position. Upon reaching its normal position, a circuit is established for sequence switch magnet 610, extending through the magnet, the upper right contact of cam 611, segment 636, brush 627 to ground, at the lower left contact of cam 613, and the sequence switch is advanced into normal position. As soon as the sequence switch leaves 30 position 16, the previously traced circuit of relay 637 is opened and that relay deenergizes. All of the circuits of the incoming selector are now in normal condition. When the sequence switch 610 left position 15 $\frac{1}{4}$, the circuit, extending from ground over the right contacts of cam 614, brush 623, conductor 626, the left front contact of relay 721, the normal contact of relay 724 to battery, through the left winding of relay 721, was 35 opened and relay 721 deenergized. Upon deenergizing, relay 721 closes a circuit from ground at its right back contact, upper contacts of cam 709, to battery through the left winding of relay 700, causing the energization of relay 700. Relay 700, upon energizing, establishes a circuit from ground over the upper contact of cam 708, left front contact of relay 700, upper right contact of cam 712, to battery through the winding of sequence switch magnet 710 for advancing 40 the sequence switch into position 16. Since

the called subscriber has already hung up his receiver when sequence switch 710 reaches position 16, relay 700 being now deenergized, a circuit is established through the sequence switch magnet, the lower right contact of cam 712, the left back contact of relay 700 to ground at the upper contact of cam 708 for advancing sequence switch 710 into position 17. In position 17, a circuit is established for advancing sequence switch 710 into position 18, extending over the lower right and upper left contacts of cam 709 to ground at the right back contact of relay 721. A circuit is now established for the down-drive magnet 744, extending from battery, through this magnet, the lower contact of cam 711, the right contact of cam 707 to ground at the upper left contact of cam 706 for driving the switch shaft downwardly into its normal position. As soon as the switch shaft reaches its normal position, brush 738 engages the normal segment 713 closing a circuit for advancing sequence switch 710 into its normal position, which circuit may be traced through the magnet winding of the sequence switch, the upper left contact of cam 712, segment 713, brush 738 to ground at the upper left contact of cam 706. All apparatus employed in the establishment of the connection has now been 85 restored to normal condition.

Reringing the called subscriber.

If the toll operator at position 125 desires to rering the called subscriber while the sequence switch of the district selector 350 is in position 15, the sequence switch of the incoming selector 650 is in either of the ringing positions 13 or 15 and the sequence switch of the final selector is in position 15 for talking, she may do so by operating her 100 ringing key 102, thereby applying ringing current to the sleeve conductor of the cord circuit. When ringing current is applied to the sleeve conductor of the cord circuit, relay 100, which is adjusted to respond to ringing current, operates, intermittently opening and closing the composite leg of the toll line 150. The operation of key 102 also disconnects the supervisory equipment of the 105 cord circuit during the ringing period.

It will be noted that relays 124 and 118 are connected in parallel to the composite leg of the toll line so that when relay 100 disconnects ground from the composite leg of the toll line, the condenser 143 associated with the winding of relay 118 will charge from the battery 138 associated with the armature of relay 126 through the windings of 110 relays 124 and 118, and when ground is reconnected to the composite leg by the deenergization of relay 100 the condenser 143 will discharge through relay 118 to ground so that relay 118 will be intermittently energized. Relay 118 is, however, designed to 115

remain operated so long as the ringing current is applied to the toll line, and in operating causes relay 353 to be operated in a circuit which may be traced from ground, 5 contact of relay 118, inner right contact of relay 131, conductor 144, brush 297, terminal 296, upper contacts of cam 344 to battery through the winding of ringing relay 353. Relay 353 in operating causes the application of ringing current from the source 10 363 to the established connection to cause the signaling of the called subscriber. It will be noted that the relay 353 will follow the operations of the operator's ringing key 15 102 and that ringing current will be applied from the incoming selector to the called line upon each operation of the operator's ringing key. The manner in which the incoming selector functions to rering the wanted 20 subscriber, will not be described herein. Reference may be had to the Patent No. 1,575,299 issued to William C. Weaver, March 2, 1926, for a complete disclosure of this operation.

25 Signaling the toll operator upon a permanent signal condition at the sender.

It will be recalled that at the time the sender was seized, the monitor switch 450 advanced out of normal position into position 1. At any time thereafter, if the toll operator takes down the connection before the sequence switch of the district selector 350 advances out of position 10, releasing 35 relays 410, 413 and 414, a circuit is established for wipe-out relay 439, extending from battery through the winding of this relay, over brush 440, the right front contact of relay 404, the left normal contact of relay 413 to ground at the back contact of relay 410. Relay 439 upon operating causes the release of the sender in the well-known manner. If the operator does not wipe out the connection, the monitor switch 450 advances out of position 1 under the control of 40 the slow interrupter 436, provided the operator does not immediately dial the first digit of the wanted line designation. The circuit for advancing switch 450 may be traced from battery, through the winding of magnet 408, interrupter 436, the No. 1 terminal and brush 438 of switch 450 to ground at the right contact of relay 406. When switch 450 reaches position 3, if relay 406 is still deenergized, the switch is immediately advanced into position 5 over a circuit extending through the winding and contacts of magnet 408, the No. 3 and No. 4 terminals and brush 438 of switch 450 to ground 45 at the right contact of relay 406. In position 5 a circuit is established from battery through the winding of relay 442, the No. 5 terminal and brush 441 of switch 450 to ground at the outer left contact of relay 406. Relay 442 upon energizing establishes

a circuit from ground at its contact over brush 326, the next to outer contact of relay 318, the lower contacts of cam 355, terminal 296, brush 297, the inner contact of relay 227, the outer left back contact of relay 131 70 to battery, through the winding of relay 132. Relay 132 energizes locking over its inner left contact to ground at the back contact of relay 116 and closing an obvious circuit for lamp 133. The lighting of lamp 133 75 signals the outward operator at position 136. Relay 132 also closes a circuit from ground at its outer left contact to battery through the winding of relay 123, which relay locks to ground at the contact of relay 124 and removes ground from the circuit extending over conductor 140 to battery through the winding of relay 208. Relay 208 thereupon opens the circuit of relay 211 which releases relays 214 and 119 and opens 80 the circuit of relay 303 of the district selector circuit.

At the district selector, relay 303, upon deenergizing, closes a circuit extending from ground over its inner right back contact, the right contacts of cam 320 to battery through the winding of sequence switch magnet 310 for advancing the sequence switch into position 7. In position 7, sequence switch 310 is advanced into position 8, over a circuit 95 extending from battery through the magnet winding of sequence switch 310, the lower right contact of cam 324, normal segment 366, brush 341 to ground at the upper left contact of cam 339. As soon as the sequence switch reaches position 8, since relay 307 is not operated, a circuit is immediately established from battery through the winding of sequence switch magnet 310, the lower left contact of cam 324, the outer left back contact of relay 307 to ground, at the right contact of cam 308 for advancing the sequence switch into position 9. In position 9, the circuit previously traced over the lower right contact of cam 324 is again established for 100 advancing the sequence switch into normal position. As the sequence switch leaves position 11, the circuits through relays 410 and 402 of the sender are opened and the sender releases, as previously described. 105

The outward delay operator at position 136 upon noting the lighting of lamp 133 may get in touch with the distant toll operator over the toll line 150 by inserting the plug 135 of her cord circuit in the jack 134, 110 whereupon relay 116 operates unlocking relay 132 and extinguishing lamp 133.

If the sender fails to release under the conditions just described, and therefore the monitor switch 450 is not restored to normal, 115 it will continue to count off time advancing from position 5 into position 6 under the control of magnet 408 and interrupter 436 over the circuit previously traced. In position 6, a circuit is then established from 120 125 126 127 128 129 130 131 132 133 134 135 136 137 138 139

ground at the outer left back contact of relay 406, brush 441 to battery through the lamp 451, signaling the monitoring operator that a permanent signal condition exists and 5 that the sender has not released. Should, however, the toll operator start dialing before the switch 450 reaches position 5, the register steering switch 425 will advance out of normal position as hereinbefore described, 10 and a circuit will be established for relay 406 extending from battery through the winding of this relay, brush 443, to ground, through brush 444, and the switch 450 will therefore be immediately advanced into position 7 over 15 a circuit extending from ground at brush 444, thence over brush 443, the inner left contact of relay 406 to battery through the contact and winding of stepping magnet 408 and no signal will be given the outward delay operator and the sender will not release. 20

Incomplete dialing-sender stuck.

When switch 450 reaches position 7, it is advanced under the control of interrupter 25 436 through position 8 into position 9 provided relay 406 remains deenergized due to the fact that the operator has not completed dialing. Upon reaching position 9, switch 450 advances at once into position 10 by 30 reason of the self-interrupting circuit through magnet 408, brush 438 and the right contact of relay 406. In position 10, a short circuit is closed around the left winding of relay 402, over brush 441 and the outer left 35 back contact of relay 406, increasing the current flowing through relay 402 and relay 323 to such an extent as to cause the energization of marginal relay 323. Relay 323 upon energizing locks to ground over its 40 inner right contact and the lower left contact of cam 339, and closes a circuit for relay 319 extending from battery through the winding of relay 319, the outer left contact of relay 323 to ground at the upper left contact of cam 316. Relay 319 immediately 45 locks over its inner left front contact to ground at the inner right front contact of relay 303. Relay 319 upon energizing opens the holding circuit of relay 318 which opens 50 the circuits extending to the sender and causes the release of the sender. Relay 319 also establishes a circuit from battery, through the upper winding of relay 330 and to ground at the outer left contact of relay 319 for energizing relay 330 to open the 55 trunk conductors extending back to the toll line during the release of the sender and the restoration of the district selector circuit. At its outer left contact, relay 319 also closes 60 a circuit through the alarm mechanism 369 for indicating to the maintenance man that a stuck sender condition exists. In addition, relay 323 closes a circuit for advancing sequence switch 310 out of either position 3 65 or 5 into position 4 or 6. This circuit may

be traced from battery through the winding of sequence switch magnet 310, the upper left contact of cam 324, the inner left contact of relay 323 to ground at the right contact of cam 357. With the sequence switch 310 in 70 either position 4 or 6, the switch shaft is driven upwardly to the telltale position, in which position a circuit is closed through the sequence switch magnet 310, the upper right contact of cam 324, the telltale segment 367, brush 341 to ground at the upper left contact of cam 339 and the sequence switch is advanced into position 8. As the sequence switch 310 passes through position 7, relay 307 energizes in a circuit extending 75 through its left winding, the left contacts of cam 306 to ground at the inner right contact of relay 303 closing a locking circuit for itself through its right winding, inner left contact, outer right contact of relay 319 to ground at the upper left contact of relay 316. With relay 307 energized, a circuit is 80 closed for advancing sequence switch 310 out of position 8 into position 9, which may be traced through the upper right contact of cam 324, segment 367, brush 341, the upper contact of cam 335, outer left front contact of relay 307 to ground at the right contact of relay 308. Upon reaching position 9, the sequence switch 310 is immediately advanced 85 into position 17 over the circuit previously traced through the telltale segment 367. As the sequence switch 310 leaves position 11, relay 307 deenergizes. 90

With sequence switch 310 in position 17, a circuit is closed from ground through interrupter 368, the right contacts of cam 360, terminal 229, brush 238, the intermediate right contact of relay 214, the outer right front contact of relay 228 to battery through the winding of relay 227. Relay 227 is thereby intermittently operated and in the manner previously described causes the flashing of lamp 106 at the toll operator's position. The flashing of the lamp at this time signifies to the operator that a stuck sender condition exists. The toll operator in response to the signal restores the connection by removing plug 120 from the jack 121, 105 thereby releasing the line switch circuits in the manner previously described. As soon as the line switch circuits are restored, relay 303 deenergizes, opening the holding circuit of relay 319 and closing a circuit from ground at its inner right back contact over the right contacts of cam 320 for advancing sequence switch 310 into position 18. From this point, the district selector restores in 110 the manner previously described. 115

If the district selector has completed trunk hunting at the time the stuck sender condition arises and the sequence switch 310 is in position 9 when relays 323 and 319 operate as before described, the alarm 369 is operated, relay 330 energized and the 120 125

sender released as previously described. In position 9 of sequence switch 310, a circuit is established for relay 307 extending from battery through the left winding of relay 307, the lower contacts of cam 306, the right contact of relay 302, the innermost lower contact of relay 353 to ground at the upper right contact of cam 339 and relay 307 operates advancing sequence switch 310 into position 10. In position 10, since relay 319 is energized, a short circuit is placed across the tip and ring conductors of the district link circuit extending from the upper back contact of relay 353 over conductor 370, the inner right contact of relay 319, the lower left and upper right contacts of cam 355 to the lower back contact of relay 353. With this short circuit established across the conductors of the link circuit, the incoming selector 650, or if the connection has been established to the final selector 750, the final selector is advanced to telltale. In this case, the district selector remains operated until the maintenance man, noting the operated alarm device 369, releases it.

Had dialing been completed or the sender functioned correctly, then when monitor switch 450 reached position 7 relay 406 would have been operated over brushes 443 and 444 and the switch 450 would have advanced at once into position 12. If the sender fails to release under the stuck sender condition, when switch 450 reaches position 11, the circuit of lamp 451 is again established denoting a failure of the sender to release. Since the remaining functions of the monitor switch 450 do not directly concern the present invention, they will not be further described herein.

Special calls to outward relay operator.

Should the toll operator desire a connection with the outward delay operator's position 136, she dials a code 13. In response to the dialing of the first digit 1, the A register is advanced to its first position as previously described, following which the register steering switch 425 advances to position 1. A circuit is now established for relay 423, extending from battery through the winding of this relay, contact 446 and brush 445 of the "A" register to ground at the contact of relay 415. Relay 423 energizes locking over its inner left contact to ground at the inner left contact of relay 414. The second series of impulses which would normally operate the stepping magnet 422 of the "B" register now operate the magnet 417 of the "A" register, the stepping circuit of magnet 417 extending from battery through the left winding of relay 418, winding of magnet 417, the outer left front contact of relay 423, brush 416, winding of relay 415, left

front contact of relay 413 to ground at the back contact of relay 410. Relay 423 also transfers the circuit of relay 420 for controlling complete stepping of the register magnet from the circuit of magnet 422 to 70 the circuit of magnet 417. Thus, the "A" register receives both series of impulses and, since the digits dialed are 1 and 3 respectively, takes a setting corresponding to the sum of the two digits or to position 4. In 75 position 4, a circuit is established for relay 442 extending over terminal 447 and brush 448, the outer right contact of relay 423 to ground at the inner left contact of relay 414. Relay 442 functions as hereinbefore 80 described to light the lamp 133 at the outward delay operator's position and to cause the restoration of the sender.

District selector goes to overflow on trunk 85 hunting or to telltale.

Should the district selector advance to an overflow terminal during trunk hunting, sequence switch 310 advances to position 10 as in a regular completed connection. With 90 sequence switch 310 in position 10, a circuit is closed from battery, through the winding of sequence switch magnet 310, the right contacts of cam 336, the overflow contact of commutator strip 337, brush 338 to ground 95 at the upper left contact of cam 339, and sequence switch 310 is thus advanced into position 11. In position 11, a circuit is established for relay 307 extending through its right winding, the lower left contact of cam 333, the upper right contact of cam 336, thence to ground at the upper left contact of cam 339, over the overflow segment of commutator strip 337. Relay 307 upon energizing locks over its right front contact and 100 the upper left contact of cam 333 to ground at the left contact of cam 339, and is maintained locked until the sequence switch 310 leaves position 17. Relay 307, upon energizing, establishes a circuit extending from 110 battery through the winding of sequence switch magnet 310, the upper left contact of cam 324, the outer left front contact of relay 307, the upper left contact of cam 308 to ground at the inner right contact of relay 303, advancing sequence switch 310 into position 17. In position 17, the previously traced circuit is established through interrupter 363 for intermittently operating relay 115 227 which, in turn, causes the flashing of lamp 106 at the toll operator's position. When the toll operator noting the overflow signal, as given by lamp 106, removes the plug 120 and jack 121, the operated apparatus is restored to normal in the manner 120 previously described.

Should the district selector go to telltale position during brush or group selection, during trunk hunting or, due to the fact that the brush shaft has been moved to the tell- 130

tale position by hand, sequence switch 310 is advanced into position 17 as previously described in connection with the functioning of the district circuit in response to the 5 stuck sender condition, and a flashing signal is given to the toll operator.

What is claimed is:

1. In a telephone exchange system, a calling line, a called line, a train of selector 10 switches for extending a connection between said lines, a register sender controllable over said calling line for governing the setting of said selector switches, means associated with said calling line for setting the registers of said sender, and means associated with the first switch of said train and automatically operable following the setting of the last switch of said train for causing the application of ringing current to said called line.
2. In a telephone exchange system, a calling line, a called line, a train of selector 15 switches for extending a connection between said lines, a register sender controllable over said calling line for governing the setting of said selector switches, means associated with an intermediate switch of said train for applying ringing current to said called line, and means associated with the first switch of 20 said train and operable following the setting of the last switch of said train for transmitting ringing current to said intermediate switch for initiating the operation of said ringing current apply means.
3. In a telephone exchange system, a calling line, a called line, a train of selector 25 switches for extending a connection between said lines, a register sender controllable over said calling line for governing the setting of the selector switches, means associated with the first switch of said train and operable following the setting of the last switch of 30 said train upon the terminals of the called line for applying ringing current from a first source over the established connection, a second source of ringing current associated with an intermediate switch of said train, and means responsive to ringing current from said first source for applying current 35 from said second source to said called line.
4. In a telephone exchange system, a calling line, a called line, a train of selector 40 switches for extending a connection between said lines, a register sender controllable over said calling line for governing the setting of said selector switches, means associated with the first switch of said train and momentarily operable following the setting of the last switch of said train upon the terminals 45 of the called line for applying ringing current from a first source over the established connection, a second source of ringing current associated with an intermediate switch of said train, means responsive to ringing 50 current from said first source for applying
- current from said second source to said called line, and means operable upon the response of the called subscriber to discontinue the application of ringing current from said second source. 70
5. In a telephone exchange system, a toll office, a machine switching office, a toll line extending between said offices, a train of selector switches in said latter office for extending connections to desired lines, a register sender controllable over said toll line for governing the setting of said selector switches, and means associated with the first switch of said train and operable following the setting of the last switch of said train so for causing the application of ringing current over the established connection. 75
6. In a telephone exchange system, a toll office, a machine switching office, a toll line extending between said offices, a train of selector switches in said latter office for extending connections to desired lines, a register sender controllable over said toll line for governing the setting of said selector switches, a source of ringing current associated with the first switch of said train, a relay automatically operable following the setting of the last switch of said train for applying current from said source over the established connection, and means at said toll office for also operating said relay at will. 80
7. In a telephone exchange system, a toll office, a machine switching office, a toll line extending between said offices, a train of selector switches in said latter office for extending connections to desired lines, a register sender controllable over said toll line for governing the setting of said selector switches, a signal at said toll office, and means associated with the first switch of said train for operating said signal if said sender fails to function in response to the control thereof over said toll line. 100
8. In a telephone exchange system, an incoming line, a train of selector switches for extending connections from said line to desired lines, a register sender controllable over said line for governing the setting of said selector switches, a dial associable with said line for transmitting controlling impulses to said sender, an operator's position associable with said line, a signal thereat, and means at the first switch of said train for operating said signal if no impulses are transmitted from said toll line to said sender within a predetermined period. 110
9. In a telephone exchange system, a toll office, a machine switching office, a toll line extending between said offices, a train of selector switches in said latter office for extending connections to desired lines, a register sender controllable over said toll line for governing the setting of said selector switches, an impulse transmitting device at 115
- 120
- 125
- 130

- said toll office for controlling said sender, an operator's position associative with the incoming end of said toll line, a signal thereat, and means at the first switch of said 5 train for operating said signal if no impulses are transmitted from said toll line to said sender within a predetermined period.
10. In a telephone exchange system, a toll office, a machine switching office, a toll line 10 extending between said offices, a line switch at said latter office in which said toll line terminates, a train of selector switches in said latter office for extending connections to desired lines, a register sender controllable 15 over said toll line for governing the setting of said selector switches, an impulse transmitting device at said toll office for controlling said sender, a signal at said toll office, and means at said line switch operable from said sender for operating said signal when said sender is in condition to receive impulses from said device.
11. In a telephone exchange system, a toll office, a machine switching office, a toll line 20 25 extending between said offices, a train of selector switches in said latter office for extending connections to desired lines, a signal at said toll office, and means including an interrupter in the first switch of said train 30 for operating said signal in a distinctive manner when a connection is extended to a busy line.
12. In a telephone exchange system, a toll office, a machine switching office, a toll line 35 40 extending between said offices, a line switch at said second office in which said toll line terminates, a train of selector switches for further extending connections to desired lines, a signal in said toll office, a relay at said line switch for controlling said signal, and means for operating said relay when a connection is extended to a busy line.
13. In a telephone exchange system, a toll office, a machine switching office, a toll line 45 extending between said offices, a line
- switch in which said toll line terminates at said latter office, a selector switch accessible to said line switch for further extending connections from said toll line, said selector switch being operative in selective and 50 trunk hunting movements, means for advancing said selector switch to a particular position, a lamp signal at said toll office, a relay at said line switch for controlling said signal, and means for operating said relay 55 to flash said signal if said selector switch is advanced to said particular position.
14. In a telephone exchange system, a toll office, a machine switching office, a toll line 60 65 extending between said offices, a line switch in which said toll line terminates in said latter office, a selector switch accessible to said line switch for further extending connections from said toll line, said selector switch being operative in selective and trunk hunting movements, means for advancing said selector switch to a particular position if all trunks in a group outgoing therefrom are busy, a lamp signal in said toll office, a relay at said line switch for operating said signal, and means for operating said relay to flash said signal if said switch 70 is advanced to said particular position.
15. In a telephone exchange system, a toll office, a machine switching office, a toll line 75 80 85 extending between said offices, a selector switch for extending connections from said toll line, a register switch controlling sender controllable over said toll line, means for advancing said selector switch to a particular position if said sender fails to function in response to the control thereof over said toll line, a signal at said toll office, and means at said switch for operating said signal in a distinctive manner if said switch is advanced to said particular position

In witness whereof, I hereunto subscribe my name this 11 day of December, A. D., 1923.

WILLIAM C. JORDAN.
